UNITED STATES PATENT OFFICE

FRIEDRICH TOTZEK, OF ESSEN-STOPPENBERG, GERMANY, ASSIGNOR, BY MESNE ASSIGNMENTS, TO THE KOPPERS COMPANY OF DELAWARE, OF PITTSBURGH, PENNSYLVANIA, A CORPORATION OF DELAWARE

RETORT OVEN FOR PRODUCING GAS AND COKE

Application filed November 3, 1928, Serial No. 316,975, and in Germany November 10, 1927.

My invention refers to the production of gas and coke from coal and more especially to a coking retort oven of the cross-regenerative type as described for instance in 5 U. S. Patents to Koppers 818,083, dated April 17, 1906, and 1,026,169, dated May 14, 1912.

In this type of oven the coking chambers in which the coal is gasified alternate with 10 heating walls, traversed by vertical heating flues, the coking chambers and heating walls being assembled to form a battery. Below the coking chambers and heating walls are arranged the regenerators, extending in the 15 longitudinal direction of the coking chambers and heating walls and transversely to the longitudinal axis of the battery as a whole. Ovens of this type may be heated either with their own rich gas or with ex- 20 traenuously-derived special gas such as producer gas and the like.

In the ovens described in the patents mentioned above the air or the mixture of air and gas to be preheated ascend in one half of 25 each regenerator and after having passed through the heating flues of the heating wall overlying the regenerator descend in the other half of this same regenerator. In contradistinction thereto in the coke ovens de- 30 scribed in the German patent to Koppers No. 189,148, which belongs to the same type as far as the regenerators are concerned, adjoining regenerators cooperate in pairs, the air or gases heating the coking chambers ascending 35 in one and descending in the other regenerator of each pair.

Ovens of this cross-regenerative type involve the disadvantage, more especially when 40 they shall be heated with preheated air and preheated poor gas, that the brick work partitions separating the regenerators and which are inserted between pairs of regenerators traversed in opposite directions, measure about 300-450 square feet and, on 45 the operation of the oven being started and the whole block of chambers undergoing considerable expansion, have a great tendency to crack. This formation of cracks or fissures in the brick work inevitably results in 50 losses of gas and air passing through the

brick work from the upflow to the downflow regenerators.

I have found that these drawbacks can be obviated in accordance with the present invention by arranging the regenerators for 55 communication with the heating walls in a manner, which shall be described more fully hereinafter, reference being had to the drawings affixed to this specification and forming part thereof, which disclose an improved retort oven embodying my invention diagrammatically by way of example.

In the drawings,

Fig. 1 is a longitudinal section of a heating wall of this oven and of the divided regenerator arranged below the heating wall, 65 the section being taken on the line C—C in Fig. 3.

Fig. 2 is a vertical cross-section of part of the battery of ovens on the line A—A, and 70

Fig. 3 is a similar section on the line B—B in Fig. 1.

Fig. 4 is a partial horizontal section of the battery of ovens on the line E—E in Fig. 1, 75 and

Fig. 5 is a similar section on the line F—F in Fig. 1.

Referring to the drawings, 12 (Figs. 2 and 3) are the horizontally elongated coking chambers and 11 are the heating walls, 80 these latter being here formed in a manner well known per se of a row of pairs of vertical flues *a* and *b*, each pair being separated by a vertical partition 35 and communicating with each other by a passage 36. 85 The oven here shown being designed to be operated with a change of direction of the flow of the gases in predetermined intervals, these pairs of heating flues are supplied in the first time interval with gas and air entering through separate ducts in the bottom of the flues *a*, the waste gases formed by the combustion of the mixed gas and air flowing downwards through the corresponding flues *b*. After reversal of the valves provided for this purpose the gas and air as well as the waste gases will travel in the opposite direction. The coal charged into 90 the coking chambers 12 is thus heated and 95 100

converted into coke, the gas formed being drawn off.

Underneath the oven structure formed by the alternating heating flues 11 and coking chambers 12 are arranged the regenerators 13, 15 and 14, 16, respectively, each pair serving two adjoining heating walls, and each pair extending transversely to the battery, and being filled with checkerwork. A 10 partition 17 extending across the whole length of the battery and in the middle axis thereof separates the chambers of each pair, as can best be guessed from Fig. 5, which also shows the partitions 18 extending parallel to 15 the chambers.

Whenever the regenerator chambers 13 and 14 are utilized for preheating air and poor gases, the regenerator chambers 15 and 16 are traversed in the same time interval 20 by the waste heat, while in the interval next following, when the valves have been reversed, the regenerator chambers 15 and 16 serve for preheating. This is shown in Fig. 1, where air is led into the regenerator 15 through the bottom canal 19, to be preheated to about 1000° C. in contact with the hot checkerwork and to reach the heating flues *a* of the corresponding pair of heating walls 25 11, partly directly through the short ducts 20 as far as those heating flues on the right hand side in Fig. 1 are concerned, which are positioned directly above the regenerator chambers 15 and 16, and for the other part 30 through a canal 22, which extends from the inner top corners of the regenerator first in slightly ascending and thereafter in horizontal direction above the corresponding regenerator chamber 13 and below the other halves of the heating walls 11 above the 35 chambers 13, 14. Ducts 21 connect the canal 22 with these heating walls (Figs. 1 and 2). In a similar manner gas preheated in the regenerator 16 (Fig. 5), which adjoins the regenerator 15, will pass through ducts 33 40 (Fig. 4) into those heating flues *a*, which are positioned above regenerators 15, 16 in the right hand half of Fig. 1, while the heating flues *a* on the left hand side of Fig. 1 are supplied with preheated gas from the same 45 regenerator chamber 16 by way of a canal 23 extending from the inner top corner of regenerator 16 first in slightly ascending direction and then horizontally underneath the 50 row of flues in the left hand half of Fig. 1, ducts 24 (Figs. 1, 2 and 4) connecting the 55 canal with these flues.

The waste gases descending in the flues *b* 60 on the left hand side of Fig. 1 escape through the ducts 25, 26 into the regenerator chambers 13 and 14, respectively, while the waste heat escaping from the right hand half of the heating wall flows through ducts 27, 28 and canals 29 and 30 (Figs. 1 and 4), which 65 are formed and positioned corresponding to

the canals 22, 23, into the same regenerator chambers 13 and 14, entering at the inner top corners thereof. After having passed through the chambers in contact with the checkerwork arranged therein, which is 70 heated thereby, the waste gases escape through the bottom canals 31 and 32, respectively (Figs. 1, 2, 3).

The arrangement of the canals 22, 23, 29, 30 extending on top of the regenerators and below the heating walls is such that the canals of each pair (22, 29 and 23, 30) the greater parts of which are arranged in alignment, cross each other at the inner ends, as is 80 shown in Fig. 1 for a pair of canals 22, 29.

Obviously, after the valves (not shown) have been reversed, the air and gases will flow in the opposite directions entering through bottom canals 31, 32 and escaping 85 through canals 19.

As the drawings show, each gas particle, no matter which way it may travel within the battery, always encounters the same total resistance, as the distances through which it passes are always equally long. Common separating walls, in contact with which fresh air and gases on the one side and waste heat on the other must be conducted, occur merely 90 between the inner crossed portions of the canals. In view of the fact that these separating walls are arranged in the middle of the oven system, where no remarkable expansion takes place, the danger of cracking 95 and a loss of gas is obviated.

I wish it to be understood that I do not desire to be limited to the exact details of construction shown and described for obvious modifications will occur to a person skilled in the art. 100

I claim:

1. A coke oven battery comprising a series of alternate horizontal coking chambers and heating walls therefor arranged side by side in a row, each of said heating walls comprising a row of vertical flues, two parallel rows of regenerators along opposite sides of the battery respectively and below the coking chambers and heating walls, a partition extending throughout the longitudinal middle axis of said battery and separating the two rows of regenerators, ducts directly communicably connecting the regenerator chambers on one side of said partition with flues in the portion of the oven above them, and a canal extending from the inner top corner of each regenerator chamber first slightly ascending and then in substantially horizontal direction above the regenerator chamber and below the levels of the bottoms of the flues on the other side of said partition, and ducts communicably connecting each canal with flues in the portion of the oven above the same, the ascending portions of adjoining canals crossing each other in spaced relation. 115

2. A coke oven battery comprising a series of alternate horizontal coking chambers and heating walls therefor arranged side by side in a row, each of said heating walls comprising a row of vertical hairpin flues, two parallel rows of regenerators along opposite sides of the battery respectively and below the coking chambers and heating walls, a partition extending throughout the longitudinal middle axis of said battery and separating the two rows of regenerators, ducts directly communicably connecting the regenerator chambers with one of the branches of each of the flues in the portion of the oven above them, 15 a canal extending from the inner top corner of each regenerator chamber first in slightly ascending and then in substantially horizontal direction above the regenerator chamber and below the level of the bottoms 20 of the flues on the other side of said partition, and ducts communicably connecting each canal with one of the branches of each of the flues in the portion of the oven above the same, the ascending portions of adjoining canals crossing each other in spaced relation. 25

3. A coke oven comprising a row of juxtaposed vertical flues, a regenerator parallel thereto and below the levels of the bottom of part of said row of flues, means directly communicably connecting said regenerator with alternate flues of said part, and a canal communicating with and extending from one end of said regenerator below the levels of the other part of said row and also communicating with alternate flues of said other part. 30

4. A coke oven comprising a row of juxtaposed vertical flues, two regenerators arranged in line parallel to said row below the levels of the bottoms of said flues, means communicably connecting one of said regenerators with alternate flues in the portion of the row above it and separate means extending from the inner end of the regenerator between the other regenerator and the levels of the bottoms of the flues in the portion of the row thereabove and communicably connecting the first mentioned regenerator with the alternate flues in the portion of the row above 45 said other regenerator chamber, means communicably connecting the other regenerator with the intermediate flues in the portion of the row above it and separate means extending from the inner end of said other regenerator between the first mentioned regenerator and the levels of the bottoms of the flues in the portion of the row thereabove and communicably connecting said other regenerator with the intermediate flues in the portion of the row above said first mentioned regenerator. 50

5. A coke oven comprising a horizontal coking chamber, a heating wall therefor and parallel thereto, said heating wall comprising a row of vertical flues, two horizontal re-

generators in line parallel to said row below said coking chamber and heating wall, ducts directly communicably connecting one of said regenerators with the alternate flues in the part of the row above it, a canal communicating with and extending from the inner end of said regenerator between the other regenerator and level of the bottom of the remaining part of the row and also communicating with the alternate flues in said remaining part of the row, the other of said two horizontal regenerators communicating similarly with the intermediate flues above both of the two regenerators. 70

6. A coke oven comprising a horizontal coking chamber; a heating wall therefor and parallel thereto, said heating wall comprising a row of vertical flues, two horizontal regenerators arranged below and parallel to said coking chamber and heating wall, short direct communicating connections between each regenerator and some of the flues in the half of said heating wall for the portion of the oven above the same, a canal communicating with and extending from the inner top corner of each regenerator and between the other regenerator and the levels of the bottom of the flues in the other half of said heating wall, and means communicably connecting said canal with some of the flues in said last mentioned half of the heating wall, one of said regenerators being communicably connected as aforesaid with alternate flues and the other with intermediate flues. 90

7. A coke oven comprising a horizontal coking chamber, a heating wall therefor and parallel thereto, said heating wall comprising a row of vertical flues, two horizontal regenerators below and in line parallel to said coking chamber and heating wall, short direct communications between each regenerator and some of the flues in the half of said heating wall for the portion of the oven above the same, a canal communicating with and extending from the inner top corner of each regenerator at an angle to the horizontal and also between the other regenerator and the levels of the bottoms of the flues in the other half of said heating wall substantially parallel to said regenerator and heating wall, and means communicably connecting said canal to some of the flues in said last mentioned half of the heating wall, and one of said regenerators being communicably connected as aforesaid with alternate flues and the other with intermediate flues, and the portions of said two canals which extend at an angle to the horizontal crossing each other in spaced relation. 105

8. A coke oven comprising a horizontal coking chamber, a heating wall therefor and parallel thereto, a row of vertical hairpin flues in said heating wall, two horizontal regenerators below and in line parallel to said coking chamber and heating wall, short direct 125

communicating connections between each regenerator and some of the flues in the half of said heating wall for the portion of the oven above the same, a canal communicating with and extending from the inner top corner of each regenerator and between the other regenerator and the levels of the bottom of the flues in the other half of said heating wall and means communicably connecting said canal with some of the flues in said last mentioned half, one of said regenerators being connected as aforesaid with one branch of the hairpin flues and the other regenerator with the other branch of said hairpin flues.

15. 9. A coke oven battery comprising, in combination: a series of alternate coking chambers and heating walls therefor arranged side by side in a row; two series of regenerators situated below the oven and separated by a wall longitudinally of the battery, each of said heating walls comprising vertical heating flues, the vertical flues of each of said heating walls being communicably connected with others of the vertical heating flues of said walls so as to provide two sets of vertical heating flues operable for concurrent inflow combustion and outflow of waste gases in alternation with each other along the portions of the coking chambers in the portions of the battery above each of said series of regenerators; means directly communicably connecting each of the regenerators with some of the vertical flues in the portion of the battery above their respective series, and canal means communicating with and extending from one end of each of the regenerators between the upper portions of the regenerators of the other series and the levels of the bottoms of the flues in the portion of the battery above the other series of regenerators and communicating with some of the last mentioned flues.

10. A coke oven battery comprising, in combination: a series of alternate coking chambers and heating walls therefor arranged side by side in a row; two series of regenerators, situated below the oven, separated by a wall longitudinally of the battery and operable for concurrent inflow preheating and outflow of waste gas in alternation with each other; each of said heating walls comprising vertical heating flues, the vertical flues of each of said heating walls being communicably connected with others of the vertical heating flues of said walls so as to provide two sets of vertical heating flues operable for concurrent inflow combustion and outflow of waste gas in alternation with each other along the portions of the coking chambers above each of said series of regenerators, means directly communicably connecting each of the regenerators of one of the two series thereof with some of the flues of one of the two sets thereof along the portions of the coking chambers above said series of regener-

ators, canal means communicating with and extending from one end of each of the regenerators of said one of the two series thereof between the upper portions of regenerators of the other series thereof and below the levels of the bottoms of the flues above the other series of regenerators and communicating with some of the flues of said one of the two sets thereof along portions of the coking chambers in the portion of the battery above said other series of regenerators; and each of the regenerators of the other of the two series thereof communicating similarly with some of the flues of the other of the two sets thereof along the portions of the coking chambers above both of said two series of regenerators.

11. A coke oven battery comprising, in combination: a series of alternate coking chambers and heating walls therefor arranged side by side in a row, two series of regenerators, situated below the oven, separated by a wall longitudinally of the battery, and operable for concurrent inflow preheating and outflow of waste gas in alternation with each other, extension passageway means extending from each regenerator between the upper portions of the regenerators of the other series and the levels of the bottoms of the flues in the portion of the oven above said series, each of said heating walls comprising pairs of vertical flues communicably connected with each other for concurrent inflow combustion and outflow of waste gas in alternation with each other, there being pairs of such flues along portions of the coking chambers on opposite sides of the separating wall; one flue of each of the aforesaid pairs communicating directly with a regenerator of the series on the same side of the battery that the pair of flues is on and the other flue of each pair communicating through an extension passageway with a regenerator of the other series.

12. A coke oven battery comprising, in combination: a series of alternate coking chambers and heating walls therefor arranged side by side in a row, each of said heating walls comprising vertical heating flues; two series of regenerators situated below the oven and separated by a wall longitudinally of the battery; means substantially directly communicably connecting regenerators of each of said series with some of the vertical flues in the portion of the oven above their respective series; and canal means communicating with and extending from one end of regenerators of each of said series between the upper portions of the regenerators of the other series and the levels of the bottoms of the flues in the portion of the battery above said other series of regenerators and communicating with some of the last mentioned flues.

13. A coke oven battery comprising, in

- combination: a series of alternate coking chambers and heating walls therefor arranged side by side in a row, each of said heating walls comprising vertical heating flues; two series of regenerators situated below the oven, separated by a wall longitudinally of the battery, and operable for concurrent inflow preheating and outflow of waste gas in alternation with each other;
- 10 means directly communicably connecting regenerators of one of the two series thereof with some of the flues along the portions of the coking chambers in the portion of the battery above said series of regenerators; canal
- 15 means communicating with and extending from one end of regenerators of said one of the two series thereof between the upper portions of regenerators of the other series thereof and below the levels of the bottoms
- 20 of the flues above the other series of regenerators and communicating with some of said flues; and the regenerators of the other of the two series thereof communicating similarly with some of the flues above both of
- 25 said two series of regenerators.

In testimony whereof I affix my signature.
FRIEDRICH TOTZEK.
